MATCH CONTAINER

Frank J. Weisgerber, Aurora, Ill.

Refiled for abandoned application Serial No.
214,618, June 20, 1938. This application June
21, 1939, Serial No. 280,354

4 Claims. (Cl. 206—31)

This application is a refile for abandoned application filed June 20, 1938, Serial Number 214,618.

5 My invention relates in general to match holders and more in particular to a telescoping match container which can be readily converted into a match holder for mounting on a smoking stand or the like.

10 It has been customary to supply matches, and particularly safety matches in a container comprising an open-ended frame having a box slideable therein to carry the matches. Smoking stands, ash receivers, and the like, have been provided with various structures adapted to support this type of match container in a manner so that one end of the matches is available above the top of the housing. In some instances a portion of the box holding the matches can be torn off at one end so that the matches are completely exposed at that end above the adjacent edge of the frame. With all of these constructions and expedients, however, the inner box still remains slideable in the frame, and may be pulled out of the housing when supported 20 on a stand, and sometimes is pushed down or moved in such a way that the matches either fall out of the box or are made inaccessible to the user.

25 It is an object of my invention to provide an improved telescoping match container which is adapted for mounting upon smoking stands or the like to expose one end of the matches therein for use.

30 It is also an object of my invention to provide a match container which is originally closed so that the matches therein are entirely covered but which includes a sliding match box in an open-ended frame which may be moved to a position to expose the matches and then anchored in place so as to remain fixed relative to the open-ended frame.

35 One of the features of my invention is the provision of a neat and simple match holder for mounting upon smoking stands and the like which can be made ready for use without tools or similar implements.

40 The principal advantage of my invention lies in the fact that after the match holder is assembled into working position, it will thereafter continuously present one end of the matches for easy accessibility without danger of the holder becoming disassembled or the matches moved out of position for accessibility.

45 50 55 Other objects, features, and advantages of my

invention will be apparent from the following description taken with the drawing in which:

Fig. 1 is a perspective view in elevation showing the match container of my invention completely assembled as a match holder and supported upon an ash receiver.

Fig. 2 is a perspective view of the match box normally adapted to slide within an open-ended frame of the complete container.

Fig. 3 is a similar illustration of the match box after it has been prepared to anchor it within the open-ended frame for holding the matches as illustrated in Fig. 1.

5 10 15 20 25 30 35 In practicing my invention I provide an open-ended frame 10 of the well-known configuration such as has been employed in the past in a match container, and particularly one for safety matches, such frame having a piece of friction paper 11 on each of two sides thereof upon which a match may be scratched to ignite the same. In the frame for the match container of my invention, however, a pair of transverse slots 12 and 13 are cut in one wall thereof as contrasted to the usual continuous wall of the frames previously employed. The sliding drawer-like box 14 adapted to slide in the frame 10 in a telescoping manner is employed to carry the matches 16 as can be understood from a consideration of Figs. 1 and 2. A box for carrying the matches of this general configuration has been heretofore employed, but with the prior art box, when the same was moved in the frame to expose the matches for use above one open end of the frame, there was nothing in the complete match container itself to prevent the box from falling out of or sliding back into the frame so that the matches were either dropped completely from the box or made inaccessible to the user.

40 45 50 55 In the illustrated embodiment of my invention the box 14 is perforated on a line transversely thereof and intermediate the ends thereof so that perforations 17 extend over each side wall and a portion of the bottom of the box to meet longitudinally extending perforations 18 which may extend substantially the entire length of the bottom of the box. Additional lines of perforations are provided at 19 in the bottom of the box joining the two longitudinal lines of perforations 18. When the box 14 is moved out of one end of the frame 10 a distance equal approximately to one-half of the length of said box, the exposed portion thereof may be grasped by the user and torn along the lines of perforations 17, and lines of perforations 18 and 19

at the end of the box which is exposed. This operation removes approximately one-half of the box 14 and a tongue 21 extends beyond the remainder of the box as shown in Fig. 3. Such tongue may be bent backwardly over the adjacent edge 22 of the frame and inserted into a slot as 13 in Fig. 1 so that the outer end T of the tongue fits between the remainder of the bottom of the box and the inside wall of the frame 10. 10. This is shown clearly in dotted lines in Fig. 1.

With the tongue 21 at the tip portion T securely locked within the frame 10 at the slot 13, the box 14 is retained against movement in either direction within the frame. Inasmuch as the paper out of which the box 14 is normally constructed is relatively stiff, when the tongue is bent over the edge 22 and locked into the slot 13 as illustrated, the rigidity of the box material will assist in the anchoring of the member. The matches 16 are normally substantially as long as the length of the box 14, when such box is positioned in the position of Fig. 1, and approximately one-half of each match will be accessible for grasping above the top of the frame. With this construction the matches will remain in this position irrespective of the construction of the holding portion 23 of the ash receiver 24, assuming of course that some configuration for this portion is provided which will frictionally engage the frame 10.

With the tongue portion 21 of the box 14 extending both ways from the center of the bottom of said box, and longitudinally thereof, it is understood that either end of the box may be torn at the perforated lines. That end of the tongue portion from which a portion of the box has been torn is then ready for insertion in a corresponding slot 12 or 13 in the frame 10. With this double assembly, it is also possible for a user to choose the particular end of the matches 16 which he wishes to make accessible. Furthermore, the double construction permits the user to assemble the box and frame into locked position irrespective of which end of the box is initially pushed out of the open-ended frame 10, and eliminate any preliminary investigation before the match holder can be prepared.

From the above description it is apparent that I provide a match container which provides greater convenience for the user, and makes possible a rigid, neat and simple holder for the matches for mounting on an ash receiver or the like to continuously present the matches for use. The assembly of the slidable match box and open-ended frame into a rigid holder for exposing the matches for use can be accomplished without the use of a knife, scissors, or similar instrument, which often would not be at hand when the user required the same. In addition, these conveniences are provided in a structure which can be manufactured at substantially the

same cost as the structures of the prior art without such improvements.

Although I have described my invention in its preferred embodiment, it is understood that the invention is not limited thereto, but changes and 5 modifications may be made therein all within the scope of the appended claims.

I claim:

1. A match container comprising an open-ended frame, a match box slidable therein for 10 carrying matches, said match box having two side walls and a bottom portion between the same with perforations extending transversely of each side wall and over said bottom for removing substantially one-half of said box in a tearing action, a tongue extension on the bottom of said box, and a slot in one side of the open-ended frame to receive said tongue for securing said box in a position nearer to one end than to an opposite end of said frame to expose the 20 matches in said box for use.

2. A match container including a frame having a pair of openings in one wall thereof spaced apart longitudinally in said wall, a match box 25 slidable in said frame, said box having lines of perforations therein positioned in such a manner as to permit the tearing of one-half portion or the other of said box from the entire box upon positioning of said box adjacent to one end or to an opposite end of said frame, with a locking 30 extension remaining on said bottom irrespective of the particular half portion removed, and with said locking extension adapted for locking engagement with the frame-wall opening adjacent the end of the frame in which the box is positioned.

3. A match container including an open-ended frame having an edge at each end, said frame having a transverse slot therein positioned intermediate said frame end edges, a match box 40 slidable in said frame having a tongue thereon folded outwardly over a frame end edge and extending longitudinally of the frame and inserted in said transverse slot to prevent the match box from sliding with reference to the frame 45 when supporting the match container at the frame.

4. A match container including an open-ended frame having an edge at each end, said frame having a pair of transverse slots therein with 50 one slot adjacent each of said frame end edges, a match box slidable in said frame having a pair of longitudinally and oppositely extending tongue portions, with one of said tongue portions folded outwardly over one of said frame end edges and extending longitudinally of the frame and inserted in the transverse slot adjacent said one frame end edge to prevent the match box from sliding with reference to the frame when supporting the match container at the frame.

FRANK J. WEISGERBER.
